CLAIM

The ornamental design for a bank note sorting and counting machine, as shown and described.

DESCRIPTION

FIG. 1 is a perspective view of a bank note sorting and counting machine according to a first embodiment of our new ornamental design;

FIG. 2 is a front elevation view thereof;

FIG. 3 is a right side elevation view thereof;

FIG. 4 is a left side elevation view thereof;

FIG. 5 is a top plan view thereof;

FIG. 6 is a perspective view of a bank note sorting and counting machine according to a second embodiment of our new ornamental design;

FIG. 7 is a front elevation view thereof;

FIG. 8 is a right side elevation view thereof;

FIG. 9 is a left side elevation view thereof; and,

FIG. 10 is a top plan view thereof.

The bottom and rear sides of the first and second embodiments, which are not shown, do not form any parts of the claimed design.

The broken lines showing environment or structure are for illustrative purposes only and form no part of the claimed design.
